CUSHIONING MECHANISM

Leverett M. Clark, Snyder, N. Y., assignor to
 Waugh Equipment Company, New York, N. Y.,
 a corporation of Maine

Application June 2, 1937, Serial No. 145,963

11 Claims. (Cl. 213—32)

This invention relates to a cushioning mechanism of the energy-absorbing type and is concerned more particularly with a novel friction cushioning mechanism which may be employed for various purposes, for example, as a draft gear for railway equipment or in connection with buffers, trucks, etc. The new cushioning mechanism has a wide range of utility but, since it may be employed to especial advantage as a draft gear, an embodiment of the invention suitable for that purpose will be illustrated and described for purposes of explanation.

As is well known, draft gears employed on railway vehicles to protect their structure and lading against the shocks to which they are subjected during switching and when in train service, should have high energy absorption, low resistance, smooth action, and sustained initial compression. The new device is so constructed as to have these characteristics and, in addition, it is rugged and durable and of relatively light weight.

The new cushioning mechanism comprises a casing, preferably cylindrical in form, which encloses the operating elements of the device and, in one end, is provided with an internal friction generating surface, preferably of frusto-conical form. Friction shoes, lying side by side in a circular series, engage the friction surface and, extending within the group of shoes and projecting outwardly beyond them, is an actuating plunger which has wedging surfaces engaging similar surfaces on the shoes. Movement of the shoes into the casing is resisted by spring means and, to insure that the shoes will take part equally in the cushioning action, the shoes are sub-divided into two groups with the members of the groups lying in alternation. Spacer and equalizer elements are mounted within the casing to engage the shoes and the spacer element has parts engaging all of the shoes and holding them properly spaced circumferentially of the friction generating surface, and other parts by which forces lengthwise of the casing are transmitted to the shoes of one group. The equalizer engages the shoes of the other group for transmitting thereto forces applied lengthwise of the casing and the spring means takes the form of a pair of coil springs concentrically arranged, one spring acting on the spacer element and the other on the equalizer element. The springs are under substantially the same initial loading and have substantially the same characteristics so that they operate with the same effect to resist inward movement of the shoes of the two groups.

For a better understanding of the invention,

reference may be made to the accompanying drawings in which:

Figure 1 is a view in longitudinal section of the device used as draft gear;

Figure 2 is a view similar to Figure 1 showing the device under compression and with certain parts illustrated in elevation;

Figure 3 is an end view of the device;

Figures 4 and 5 are sectional views on the lines 4—4 and 5—5, respectively, of Figure 1;

Figure 6 is a developed view showing the arrangement of the shoes and the spacer and equalizer elements;

Figure 7 is an elevational view of the inner surface of the shoe;

Figures 8 and 9 are opposite end views of the shoe;

Figures 10 and 11 are plan and elevational views, respectively, of the equalizer element; and

Figures 12 and 13 are plan and elevational views, respectively, of the spacer element.

Referring to the drawings, the device is illustrated at Figure 1 as including a casing 20 which is preferably of cylindrical formation, since a casing of that shape permits expansive stresses to be readily equalized. At one end, the casing is closed and at this end is a flange 21 of generally rectangular shape. In the installation shown in Figure 1, the casing lies between the usual longitudinal sills 22 of a railway vehicle and the flange 21 engages draft stops 23 secured to the sills in the usual manner.

The opposite end of the casing is open and adjacent this open end, the casing is formed with an internal friction generating surface 24 which may be and preferably is a frusto-conical formation. The surface is of sufficiently large area to obtain the necessary cushioning capacity without undue abrasion and the inward taper of the surface provides the proper rate of capacity increase of the device in operation. Within the casing at the open end, are friction shoes 25, each of these shoes being arcuate in section with the outer curved surface in contact with the surface 24 of the casing. The curvature of the friction surfaces of the shoes is so related to that of the surface 24 that the maximum contact is obtained when the shoes are at the limit of their inward movement into the casing. Each shoe is formed on its rear surface with a transverse lug 26, one lateral surface 27 of which is flat while the opposite lateral surface 28 is inclined. Extending from the surface 27 lengthwise of the shoe is a rib 29 and the end of the shoe may have a recess 30 in alignment with the rib.

An actuating plunger 31 having a circumferential inclined wedging surface 32, is mounted to extend within the series of shoes with the wedging surface 32 contacting with the surface 28 on the shoes. The plunger has a stem 33 with a bore therethrough and a bolt 34 passes through the bore and has a nut 35 which lies in a recess 36 in the outer end of the plunger. The bolt projects through the closed end of the casing 10 and at that end has a head 37 lying within a recess 38 in the casing end. The bolt limits the outward movement of the plunger relative to the casing.

Within the group of shoes is a spacing element 15 39, having the form of a ring and provided with radial recesses 40 in its outer surface, the recesses being equally spaced so that each one may receive the rib 29 of a shoe. On opposite sides of alternate recesses are outwardly extending lugs 41 which bear against the flat lateral surfaces 27 of lugs 26 of alternate shoes. When the spacer is in position, the interengagement of the ribs of all the shoes in the notches 40 causes the spacer to hold the shoes in properly spaced 20 circumferential relation and the lugs 41 on the spacer engaging the abutment surfaces 27 of lugs 26 of the shoes of one group permit forces lengthwise of the casing to be transmitted through the spacer to the shoes of one group only. 25

At the inner end of the series of shoes is an equalizer element 42 through which forces lengthwise of the casing are transmitted to the shoes which are not engaged by the lugs 41 of the spacer. The equalizer, accordingly, contacts with the shoes 30 of the second group only and for this purpose may have the form of a ring provided on one face with a plurality of projections 43, each of which has a pair of flat end surfaces 44 separated by a rib 45. The equalizer is mounted in position with the 35 ribs 45 entering the notches 30 in the shoes of the second group and the end portions on either side of the notch at the end of each such shoe bear against a pair of surfaces 44 on the equalizer. The ribs 45 are of smaller dimensions than the 40 notches in which they are received so that the equalizer takes no part in maintaining the shoes of the series in proper circumferential relation.

Mounted within the casing are inner and outer coil springs designated 46, 47, respectively, these 45 springs bearing against the closed end of the casing and against the spacer and equalizer elements, respectively, and the end convolutions of each spring are preferably flattened, as indicated at 48, so that the springs may have a good bearing against the inner end wall of the casing and against the flat faces of the spacer and equalizer. The springs are installed under substantially the same initial loading and they are of similar resistance characteristics so that inward movement of all the shoes will be equally resisted by the two springs. 50

Outside the casing and in engagement with the outer end of the actuating plunger is a follower block 49 which engages draft stops 50 secured to 55 the sills 22 in the usual manner. A yoke 51 encircles the cushioning mechanism and follower block, and the yoke at its forward end receives the shank 52 of a coupler, the rear end of which bears against the outer face of the follower block.

In the operation of the device as illustrated, its 60 overall length is shortened by the plunger being forced into the casing, carrying the shoes with it and thereby generating friction. In draft, the casing is moved relative to the shoes and plunger 65 by the rear end of yoke 51 which is drawn forward

by the coupler, while in buff, the shoes and plunger are forced into the casing by the coupler shank acting against the follower 49. The inward movement of the plunger and shoes relative to the casing takes place against the resistance of the 5 springs, and the force of the springs acting through the wedging surfaces on the shoes and plunger tends to force the shoes radially outward. Friction is developed between the shoes and the conical surface in the casing in part by the action 10 of the springs tending to force the shoes outwardly, and in part by the decreasing diameter of the surface.

In the normal or released position of the mechanism, the springs exert a pressure of the order of 15 6000 to 7000 pounds, and this pressure acting through the engaging surfaces of the shoes and plunger forces the shoes radially outward against the conical surface in the casing, and offers resistance to inward movement of the shoes, constituting what is known as the "initial compression of the mechanism". Whenever a force of sufficient magnitude is applied to the cushioning device to overcome the initial compression, the plunger and shoes are moved into the casing, with 20 the result that the casing is subjected to expansive stresses. During the inward movement of the shoes, the radial pressure tends to increase until the reaction of the casing under expansion, operating through the coating surfaces on the 25 shoes and plunger, overcomes the adhesion of the surfaces to each other and produces a movement of the shoes inwardly with respect to the plunger. This results in the reduction in the effective outside diameter of the group of shoes and correspondingly reduces the pressure of the shoes against the casing. In certain prior devices of this sort, the static adhesion of the parts is so great that the inward movement of the friction generating elements relative to the plunger or actuating member is delayed to a point near complete closure of the device, with the result that high 30 radial pressures are exerted upon the casing, and extremely high forces are transmitted to the vehicle structure. In the device of the invention, 35 the subdivision of the six shoes into groups of three insures equal initial pressures of all of the shoes against the friction surface of the casing, and because of the balanced pressure distribution, the static adhesion between the engaging surfaces 40 on the shoes and plunger is of relatively low value and the slipping of the shoes relative to the plunger may occur several times during the compression of the device. When the compressive 45 force is removed, the expansive force of the casing acts through the shoes to cause the plunger to be expelled slightly with respect to the shoes. The pressure of the shoes against the casing is 50 thereupon reduced to that arising from the action 55 of the coil springs, and since the frictional engagement of the shoes and casing can be overcome by that component of the spring force which is directed outwardly, the springs act at once to restore the operating parts to their normal or 60 released position.

The springs employed have a relatively high capacity in the normal condition of the device and their capacity does not greatly increase during the closing of the mechanism, with the result 65 that a relatively small amount of energy is stored in the springs during closure and subsequently delivered in the form of recoil during release. The maximum capacity of the springs may be relatively small as compared with the capacity of the 70 75

springs employed in similar cushioning devices of former constructions.

The device is generally similar in operation to that disclosed in my prior Patent No. 2,052,166, 5 August 25, 1936, but differs therefrom in that the shoes are sub-divided into two groups with the inward movement of the shoes of each group resisted in part by a separate spring. In the device of the patent, it has been found that as a result 10 of variations in the formation of the shoes, certain shoes may not bear firmly against the friction surface, so that these shoes take less part in the generation of friction than the others. Preferably, six shoes are employed in the patented device 15 and it is difficult, within the limits of cost permitted, to construct that device in such manner that all six shoes will function equally. In the present device, six shoes are employed but, because of the sub-division of the shoes into two 20 groups of three, a three point bearing of each group of shoes on the friction surface is thereby obtained. This makes it possible to insure that all of the shoes will take part equally in the generation of friction.

25 In the new device, the springs are wound in the same direction and as the springs are compressed, the ends have a rotary movement in one direction and the reverse movement occurs when the springs expand. During the compression of the 30 device with the shoes moving inward, the engagement of the shoes with the friction surface of the casing prevents the rotary action of the ends of the springs from having any effect, but torsional energy is stored in the springs. When the 35 external pressure is removed, the initial reaction of the shoes momentarily lessens their engagement with the surface of the casing to such an extent that the stored torsional energy in the springs produces a slight movement of the spacer 40 and equalizing elements, the former acting to rotate the shoes within the casing. As a result, the shoes shift circumferentially with respect to the friction surface during a series of operations, and the possibility of the shoes wearing grooves 45 lengthwise of the surface is avoided. In those devices in which such groove wear takes place, the expansive stresses ultimately become unbalanced and the casing may fail prematurely in service. Also, in those devices in which the friction surface 50 becomes grooved, a blow of unusually high magnitude will occasionally cause the shoes to become displaced circumferentially, with the result that the shoes may contact with only relatively small ridges. During subsequent closure of 55 the mechanism, sufficient heat may be developed on these small areas of contact to cause the shoes and casing to become partially welded together with the result that the mechanism fails to release. In the present device, these objectionable 60 results of wear on the casing are presented.

The new device affords the several advantages made available by the device of the patent, and, in addition, is so constructed to insure that all shoes will take part equally in the operation. This 65 insures that devices of the new construction will all have similar operating characteristics.

I claim:

1. A cushioning mechanism which comprises a casing, a circular series of friction shoes in the 70 casing with the shoes arranged in two groups, the members of the groups alternating in the series, a central actuating plunger extending within the series of shoes, the plunger and shoes having cooperating wedging surfaces, a spacer having parts engaging all the shoes to hold them circumfer-

entially spaced and other parts engaging the shoes of one group only, an equalizer engaging the shoes of the second group only, and a pair of springs within the casing and acting on the shoes, one spring resisting the inward movement of the 8 shoes of the first group and the other resisting the inward movement of the shoes of the second group.

2. A cushioning mechanism which comprises a casing, a circular series of friction shoes in the 10 casing with the shoes arranged in two groups, the members of the groups alternating in the series, a central actuating plunger extending within the series of shoes, the plunger and shoes having cooperating wedging surfaces, a spacer having 15 parts engaging all the shoes to hold the shoes properly spaced circumferentially and other parts engaging the shoes of one group only, an equalizer engaging the shoes of the second group only, and a pair of springs within the casing, one spring 20 engaging the spacer and the other the equalizer, said springs, respectively, resisting inward movement of the shoes of the two groups.

3. A cushioning mechanism which comprises a casing, a circular series of friction shoes in the 25 casing with the shoes arranged in two groups, the members of the groups alternating in the series, a central actuating plunger extending within the series of shoes, the plunger and shoes having 30 cooperating wedging surfaces, a spacer having parts engaging all the shoes to hold them circumferentially spaced and other parts engaging the shoes of one group only, an equalizer engaging the shoes of the second group only, and a pair of coil springs within the casing engaging, respectively, the 35 spacer and equalizer and resisting inward movement of the shoes, said springs being wound in the same direction.

4. A cushioning mechanism which comprises a 40 casing, a circular series of friction shoes in the casing in engagement with a wall of the casing, the shoes being arranged in two groups with the members of the groups alternating, a central actuating plunger extending within the series of shoes, the plunger and shoes having cooperating 45 wedging surfaces, means connecting the plunger and casing and limiting the movement of the plunger outward from the casing, spacer and equalizer elements in the casing, one of said elements engaging all the shoes to retain them in 50 proper circumferential spacing and having parts engaging the shoes of one group to transmit thereto forces acting lengthwise of the casing, the other element engaging the shoes of the second group to transmit thereto forces acting lengthwise of the casing, and a pair of springs within 55 the casing acting, respectively, through the individual elements to resist inward movement of the shoes.

5. In a cushioning mechanism, the combination of a circular series of friction shoes, each shoe having an outer arcuate friction surface, a pair of spaced operating surfaces, and a wedging surface, a spacer element having parts interengaged with all the shoes of the series to hold the shoes 60 in proper circumferential relation and having operating surfaces engaged with one operating surface of each of the alternate shoes in the series, an equalizer element having surfaces engaging the other operating surfaces of all the remaining 65 shoes, and a pair of springs engaging the spacer and equalizer elements, respectively.

6. In a cushioning mechanism, the combination of a casing, a circular series of friction shoes in the casing with the shoes arranged in two groups, 70

the members of the groups alternating in the series, a central actuating plunger extending within the series of shoes, the plunger and shoes having cooperating wedging surfaces, separate 5 spring means between one end of the casing and the respective groups of shoes, a member interposed between one spring means and surfaces on the shoes of one group only for receiving and transmitting the force of that spring to the shoes 10 of that group only, the other spring means acting on different parts of the shoes of the other group only, and means for limiting the movement of the plunger out of the casing.

7. In a cushioning mechanism, the combination 15 of a casing, a circular series of friction shoes in the casing with the shoes arranged in two groups, the members of the groups alternating in the series, a central actuating plunger extending within the series of shoes, the plunger and shoes 20 having cooperating wedging surfaces, a pair of springs lying one within the other between one end of the casing and the shoes, one spring acting on the inner ends of the shoes of one group only to resist inward movement of said shoes, a member 25 interposed between the other spring and different parts of the shoes of the second group only, said other spring resisting the inward movement of the shoes of the second group only, and means limiting the movement of the plunger out of the 30 casing.

8. In a cushioning mechanism, the combination 35 of a casing, a circular series of friction shoes in the casing with the shoes arranged in two groups, the members of the groups alternating in the series, a central actuating plunger extending within the series of shoes, the plunger and shoes having 40 cooperating wedging surfaces, a pair of coil springs lying one within the other between one end of the casing and the shoes, a member interposed between the shoes of one group and the adjacent end of the inner spring for receiving 45 and transmitting the force of that spring to surfaces of the shoes of said group only, the outer spring acting on other surfaces of the shoes of the other group only, and means limiting the movement of the plunger out of the casing.

9. In a cushioning mechanism, the combination 50 of a casing having a friction generating surface, a closed series of six friction shoes in the casing having surfaces in engagement with the friction generating surface of the casing, the shoes forming two groups of three shoes each with the members of the groups in alternation, a central actuating plunger extending within the series of shoes,

the plunger and shoes having cooperating wedging surfaces, a member engaging surfaces of the shoes of one group only, a spring engaging one end of the casing and said member to resist inward movement of the shoes of said group, a 5 second spring engaging said end of the casing and acting through end surfaces of the shoes of the second group only to resist inward movement of the shoes of said group, and means for limiting the outward movement of the plunger relative to the 10 casing.

10. In a cushioning mechanism, the combination 15 of a casing having a friction generating surface, a closed series of six friction shoes in the casing having surfaces in engagement with the friction generating surface of the casing, the 20 shoes forming two groups of three shoes each with the members of the groups in alternation, a central actuating plunger extending within the series of shoes, the plunger and shoes having cooperating wedging surfaces, a spring engaging one end of the casing and exerting a force against surfaces of the shoes of one group only to resist movement of the shoes of said group into the casing, said surfaces being disposed between the ends of said 25 shoes, a second spring engaging said end of the casing and exerting a force against end surfaces of the shoes of the other group only to resist inward movement of the shoes of said group, and means for limiting the outward movement of the 30 plunger relative to the casing.

11. In a cushioning mechanism, the combination 35 of a casing having a friction generating surface, a closed series of six friction shoes in the casing having surfaces in engagement with the friction generating surface of the casing, the shoes forming two groups of three shoes each with the members of the groups in alternation, a central 40 actuating plunger extending within the series of shoes, the plunger and shoes having cooperating wedging surfaces, a spring engaging one end of the casing and exerting a force against surfaces of the shoes of one group only to resist movement of the shoes of said group into the casing, a second spring engaging said end of the casing and exerting a force against surfaces of the shoes of the other group only to resist inward movement 45 of the shoes of said group, said surfaces on the shoes of one group being disposed at places on said shoes different from the locations of said surfaces on the shoes of the other group, and means for limiting the movement of the plunger outwardly from the casing.

LEVERETT M. CLARK.
